UNITED STATES PATENT OFFICE.

JOSEPH SACHS, OF HARTFORD, CONNECTICUT, ASSIGNEE, BY MESNE ASSIGNMENTS,
TO THE HART & HEGEMAN MANUFACTURING COMPANY, OF HARTFORD, CONNECTI-
CUT, A CORPORATION OF CONNECTICUT.

PLUG-AND-SOCKET CONNECTOR.

1,135,206.

Specification of Letters Patent. Patented Apr. 13, 1915.

Application filed August 30, 1912. Serial No. 717,942.

To all whom it may concern:

Be it known that I, JOSEPH SACHS, a citizen of the United States, residing at Hartford, in the county of Hartford and State of Connecticut, have invented certain new and useful Improvements in Plug-and-Socket Connectors, of which the following is a specification.

My invention relates to improvements in connecting devices and may be termed a "plug and socket connector", one of the principal objects being to provide a device of this character having simple and effective means for securely and positively yet detachably, holding the members thereof together, the construction being such that the connecting and locking relation is quickly obtained by a relatively small amount of movement of one of said members with respect to another. This feature is in itself highly advantageous but more especially so when the device is used as an electric attachment connector in conjunction with a flexible conducting cable extending to an incandescent lamp, fan or other appliance, as when so used, expeditious connection of the extension with the minimum inconvenience and trouble is assured and the twisting or kinking of the extension wires or cables practically eliminated owing to the small amount of rotative motion of the relatively movable member of the connector which may be either member, but is preferably the plug member.

In the drawings accompanying and forming a part of this specification I have shown several of the embodiments of my invention fully set forth in the following description. I do not restrict myself, however, to such showing as I may depart therefrom in several respects within the scope of the invention defined by the claims.

Referring to the drawings: Figure 1 is an elevation of an electric attachment plug embodying my invention and adapted for use with a standard socket. Fig. 2 is a vertical section of the same.

Like characters refer to like parts throughout the several views.

Referring to Figs. 1 and 2, the attachment plug therein shown is generally denoted by 2 and is adapted to be used in the ordinary standard Edison screw socket or receptacle. The socket is usually connected

to the supplying circuit, while the plug is 55 associated with the extension cable or wires, the terminals of which are connected to contacts on the plug. The complete plug structure consists of two main and easily separable parts, 3 and 4.

The head or upper portion 5 of the part 3 consists of a cap of insulating material and the threaded conducting shell 6, which on its unthreaded end is secured to the cap 5, and at its opposite end has the internal beveled, cone seated or counter-sunk flange 7. Extending longitudinally along the threaded portion of the shell, are the slits 8, of which there may be any desired number and whereby the portions of the shell between 70 the slits act as resilient tongues or fingers 8" so that when these are expanded or forced outwardly the thread diameter of the threaded shell is increased or expanded.

The inner or central part 4 comprises the 75 core 9 of insulating material, having the cylindrical portion 10 and the enlarged bottoming portion 11, and associated with the core 9, and forming therewith the complete inner or central part of the plug, is the screw- 80 shell connecting and locking sleeve 12 which surrounds the upper side of the enlarged bottoming portion 11 of the core and a part of the cylindrical body portion 10, and to which one of the wires of the flexible extension cable is connected, a connection plate in a recess on the bottoming end of the enlarged portion of the core, being connected with the other wire of the cable as will hereinafter appear.

The locking and connecting sleeve 12 is secured to the core 9 by projections 13 on said sleeve received in recesses in the enlarged portion 11 of said core, and this end of the sleeve is formed to present a beveled or conical surface 14 around its circumference said sleeve at the other end being also formed to present a similar beveled or conical circumferential surface 15, leaving the circumferential recess or groove 16, between 100 the two cone steps of said sleeve 12. Secured to the latter is the connector 17, with its screw 18, under the head of which one of the wires is placed and thereby firmly connected to the sleeve. The core 9 at its cylindrical body portion 10 has a longitudinal groove or recess 19, accommodating this connector. The sleeve 12 is held against

2
tation by the locking projections 13 shown and the connector 17 fitting in the recess 19. The plate 20 is securely held in the recess 21 at the bottoming end of the enlarged portion 11 of the core 9 by the eyelet 22. The hole 23 passing longitudinally through the core is round for a short distance from the bottoming end up and oval for the balance of the distance. The end of the eyelet projects slightly into the oval portion of the hole and is curled over thus securely holding the plate 20. The wire to be connected with the central bottoming contact passes through the hole in the core and has its end wound around the head of the screw 21 which when screwed down so that the washer head 25 rests on the bottoming end of the plug, forms the central bottoming contact of the plug and is intended to coact with and abut against the central contact in the socket or receptacle.

When the two parts of the plug are associated as shown in Figs. 1 and 2, the internal conical or counter-sunk flange 7 at the end of the screw shell 6 rides on the coned surface 14 of the sleeve 12 secured to the core 9 and consequently when pressure is applied to force the core 9 with its enlarged and coned surface bottoming end farther up into the shell, the riding of the coned portion 14 of the sleeve 12 on the counter-sunk or cone seated internally directed flange 7 of the screw shell 6, tends to force the shell fingers or arms 8', outwardly. In the position shown in the drawings and before or when the plug is entering the socket or receptacle, the fingers or arms 8 of the longitudinally slit screw shell 6 may be forced inwardly slightly so that the thread diameter of the shell 6 is decreased.

In use, the two plug parts, 3 and 4 are separated by pulling the central part 3 out of the companion part. The flexible cable or wires are then threaded through the opening of the insulating cap portion 5 and one of said wires passing through the hole 23 in the core 9 is secured and connected to the plate 20 by the screw 24, while the other wire is connected to the connector 17 or locking sleeve 12 by means of the connector 17. The two parts of the plug are then pushed together by forcing the cylindrical body end of the core 9 back into the screw shell 6, the resilient fingers or arms 8' of which, due to the counter-sunk internal flange 7, coacting with the coned surface 15 at the upper end of the sleeve 12, ride up over this portion of the sleeve and snap into the external groove 16, as shown in the drawing.

The plug is now ready for insertion into the socket or receptacle which may be of the ordinary Edison screw shell type. Grasping the insulating cap or head 5, the plug is pushed into the receptacle so that

its bottoming end abuts and is forced against the central contact of the receptacle. The shell 6 of the plug giving inwardly permits the plug to be easily pushed into the bottoming position and the threads of the plug shell 6 snap over and engage the threads of the socket or receptacle shell. After bottoming the plug by pushing it into the socket or receptacle, it is given a slight rotative or screwing motion which results in pulling the shell 6 of the plug down slightly into the shell of the socket due to the coaction of the screw threads and at the same time the fingers or arms 8' of the plug shell 6 are forced outwardly into firmer and locking engagement with the receiving socket shell, due to the expanding action produced by the coaction of the coned surface 14 of the locking shell 12 riding on the counter-sunk or coned internal flange 7 of the plug shell 6. This locking action is exceedingly secure inasmuch as the angular relation of the locking members is such that a slight downward movement of the shell 6 into the socket produces a substantial outward movement of the arms 8' of the shell 6.

In order that the wire connection parts on the plug be relieved from as much strain as possible, each of the wires of the flexible cable is gripped between the inside of the cap 5 and the top of the cylindrical part 10 of the core portion 9 of the plug and this gripping action due to the proportion of the parts is assured when the two parts of the plug are drawn together upon insertion in the socket.

What I claim is:

1. As an article of manufacture, an electrical plug comprising a core member having a longitudinal recess, a sleeve embracing the core member, a connector fastened with in and to said sleeve and disposed in the recess, and a screw shell surrounding the sleeve provided with an expandable portion, said sleeve having means for expanding said expandable portion into contact with the wall of a socket or the movement of said plug in said socket.

2. As an article of manufacture, an electrical connecting plug comprising an insulating core member, a sleeve surrounding the core member having a cone portion, and a screw shell surrounding the sleeve and split to provide an expandable portion, the expandable portion having an inturned flange having a cone portion to coact with the cone portion of the sleeve, to secure expansion of said screw shell on the movement of the plug in a socket.

3. As an article of manufacture, an electrical plug comprising a core member having an external recess, a sleeve embracing the core member, a connector in the recess and electrically connected with said sleeve, and

a screw shell surrounding the sleeve, provided with an expansible portion, said sleeve having means for expanding said expansible portion into contact with the wall of the socket on the movement of said plug in said socket. 5

connected electrically with said sleeve, and a screw shell surrounding the sleeve provided with an expansible portion, said sleeve having means for expanding said expansible portion into contact with the wall of a socket on the movement of said plug in said socket. 15

4. As an article of manufacture, an electric plug comprising a core member and a sleeve embracing the core member, one of the parts having a projecting portion and the other a recessed portion to receive the projecting portion and thereby interlock the sleeve and the core member, a connector 10

In testimony whereof I affix my signature in presence of two witnesses.

JOSEPH SACHS.
